UNITED STATES PATENT OFFICE

161,720

FORK OR SIMILAR ARTICLE

John O. Van Koert, Newburyport, Mass., assignor to Towle Manufacturing Company, Newbury-port, Mass., a corporation of Massachusetts

Application August 30, 1950, Serial No. 11,993

Term of patent 14 years

(Cl. D54—12)

To all whom it may concern:

Be it known that I, John O. Van Koert, a citizen of the United States of America, residing at 309 Merrimac Street, in Newburyport, county of Essex, and State of Massachusetts, have invented a new, original, and ornamental Design for Fork or Similar Article, of which the following is a specification, reference being had to the accompanying drawing, forming a part thereof.

Fig. 1 is a front elevational view of a fork, showing my new design;

Fig. 2 is a cross-sectional view of the handle portion of the fork taken on line 2—2 of Fig. 1;

Fig. 3 is a cross-sectional view of the handle portion of the fork taken on line 3—3 of Fig. 1;

Fig. 4 is a cross-sectional view of the handle portion of the fork taken on line 4—4 of Fig. 1; and

Fig. 5 is a side elevation of the fork.

I claim:

The ornamental design for a fork or similar article, substantially as shown.

JOHN O. VAN KOERT.
